SOFT COLLAR OF THE TURNED DOWN TYPE

Louis L. Goldenkoff, Louisville, Ky.

Application April 3, 1941, Serial No. 386,605

3 Claims. (Cl. 2—132)

The object of the invention is a soft collar of the turned down type adapted to be braced or stiffened at the free corners by the insertion of bars of Celluloid or the like into suitable pockets of the collar.

Such pockets until now have corresponded to either of two types, being directed either parallel to the upright edges of the collar or at an angle thereto.

It has been found that for persons with a certain form of the corresponding parts of body one of these types of stiffening is best suited, and for other persons the other type of stiffening.

This means that two types of collars have to be kept on stock, which means a very undesirable complication.

It has already been proposed to overcome this drawback by providing the collar at each of the free corners with a wide V-shaped or sector-shaped pocket in which a stiffening strip is adjustable, selectively, to a plurality of angular positions around a pivot provided at its lower end. The strip is supposed to be held in the adjusted position by friction supplied by rough areas provided in the pocket.

This construction is not only much too complicated, but the strip is not held thereby in the adjusted position with any degree of reliability, and an effective stiffening of the lowermost part of said corner, part most exposed to unsightly deformation, cannot be secured in this manner.

The invention avoids all these disadvantages in an extremely simple and reliable manner by providing a soft collar of the turned down type having a multiply outer fold and having at each end of such outer fold a pair of rows of stitching, converging downwardly towards the free corner of such fold, and, within the field confined by such rows, a second pair of rows of stitching, said two pairs confining between themselves two pockets for the alternate reception of a stiffening strip in either of two predetermined fixed positions, one of these positions substantially parallel to the upright edge of said fold, the other of these positions at an angle thereto.

Further features and advantages of the invention will be seen from the following description thereof.

In the annexed drawings only so much of a collar and its production is shown by way of example as is necessary for understanding the invention, only one half of the outer fold, top or apron of a collar being shown, the inner fold or band of the collar being omitted, as not connected

with the invention. Many dimensions are exaggerated.

In the drawings is:

Fig. 1 an elevation of that ply which is to become the inner surface ply of the collar apron;

Fig. 2 an elevation of said ply in a later stage of production;

Fig. 3 a section on the line 3—3 of Fig. 2;

Fig. 4 a section on the line 4—4 of Fig. 2;

Fig. 5 an elevation of a supplement patch;

Fig. 6 an elevation like that of Fig. 2 with the supplement applied;

Fig. 7 a section on the line 7—7 of Fig. 6;

Fig. 8 a section on the line 8—8 of Fig. 6;

Fig. 9 an elevation of that ply which is to become, finally, the outer surface ply of the collar apron;

Fig. 10 an elevation of that ply which is to become, finally, the filler or insert of the apron;

Fig. 11 an elevation as seen looking upon the inner surface ply and patch after attaching to it, by sewing or stitching, the plies shown in Figs. 9 and 10;

Fig. 12 a section on the broken line 12—12 of Fig. 11;

Fig. 13 an elevation of the workpiece shown in Figs. 11 and 12 after having been turned inside out;

Fig. 14 a section on the line 14—14 of Fig. 13;

Fig. 15 an elevation of the workpiece of Fig. 13 as seen from the opposite or front side;

Fig. 16 an elevation of a stiffener strip;

Fig. 17 an elevation like Fig. 13 with the strip inserted in one of its two positions;

Fig. 18 a similar elevation with the strip in its other position.

The fabric ply 19 (Fig. 1) is to become the inner surface ply of the apron. This ply is provided with a cutout or notch 20 having two converging edges 21 and 22 resulting in a V-shaped form with the apex at 23. There a short slit 24 is provided.

The parts or stripes 25 and 26, adjacent the edges 21 and 22, are then turned over around the lines 27 and 28 and are doubled back upon the ply 19, as shown in Figs. 2, 3 and 4.

Thereafter the supplement patch 29, shown in Fig. 5, is superposed upon the ply 19 so that three of its sides coincide with the corresponding sides of said ply, whereas the fourth side 30 crosses the ply (Fig. 6).

Now the parts 19 and 29 are united by stitching i. e. they are sewn together.

One row of stitching 31 runs from the point 32 parallel to and near by the line 27 and, simul-

taniously with holding together the parts 19 and 29, secures to them and holds in place the stripe 25.

Within the field or area confined by the stitching 31 and the upright edge 33 of the collar are provided two further rows of stitching 34 and 35 parallel to the stitching 31 and the edge 33 respectively and, therefore, converging in a V-shaped form towards the point 36.

Preferably the upper ends of the stitchings 34 and 35 are bridged or connected by a row of stitching 37, parallel to and near by the edge or line 28.

The so formed triangular group of stitchings 34, 35, 37 united and holds together the parts 19, 29 and 26.

Now the outside ply 38 (Fig. 9) and filler or insert ply 39 (Fig. 10) of the same form as the ply 19, but not provided with a cutout, are assembled with the structure shown in Fig. 6 in the sequence 39, 38, 19, 29, shown in Fig. 12.

Thereupon these plies are united by the usual rows of stitching 40 and 41 parallel to and near by the upright edge 33 and the lower edge 42, respectively.

The structure now forms a wide multiply bag held together by the stitchings 40 and 41.

This bag is now turned inside out as shown in Figs. 13 and 14. Such turning or reversing is possible because, as described above, the intermediary stitchings 31, 34, 35, 37 pass only through the plies 19 and 29, but not through the plies 38, 39, as is to be seen from the front elevation Fig. 15. Consequently, the stitchings, necessary for the stiffening devices, are not visible from the outside.

The sequence of the plies is now 38, 39, 29, 19, as shown in Fig. 14.

A stiffening strip or brace 43 (Fig. 16) has a lower edge 44 so obliquely directed that the angularity of the point 45 of the strip corresponds to the angle between the stitchings 40 and 31.

By the stitching 35 and 40 is confined, between the plies 19 and 29, a channel or pocket, parallel to the upright edge 33 of the collar, for the insertion of the strip 43 in the position shown in Fig. 17.

In this position, the point 45 of the strip extends well down to the collar point 32 so that the free corner of the collar is very effectively stiffened.

The edge 44 of the strip points to the left from the point 45 in this position of the strip.

On the other hand, by the stitchings 31 and 34 is confined, between the plies 19 and 29, a channel or pocket parallel to the stitching 31 and, therefore, at an angle to the upright edge 33 of the collar.

If the strip 43 is taken out of the position of Fig. 17, turned 180° around its longitudinal axis and inserted between the stitchings 31 and 34 to the position shown in Fig. 18, the point 45 of the strip again extends well down to the collar point 32, with the side 44, as viewed from point 45 towards the other end of the strip, now pointing to the right from said point 45, so that the free corner of the collar is again very effectively stiffened. This effective stiffening, down to the extreme corner, in two different positions, is made possible by the fact, that the lower part of the pocket between the points 32 and 36 is common to both pockets or channels described.

This, therefore, is a very important feature.

The flaps or strips 25 and 26 not only form a reinforcement for the edges 27 and 28 but also have a slight yet very convenient non-rigid stiffening effect supplementing that of the strip 43.

Of course, the above described outer fold or apron of the collar is to be attached to an inner fold or band by stitching or sewing along the upper edge 46 (Figs. 14, 18). This part of the production is not described here for not forming part of the invention.

I claim:

1. A soft collar of the turned down type having a multiply outer fold and having at each end of such outer fold a pair of rows of stitching converging downwardly towards the free corner of such fold and, within the field confined by such rows, a second pair of rows of stitching, said two pairs confining between themselves two pockets for the alternate reception of a stiffening strip in either of two predetermined fixed positions, one of these positions substantially parallel to the upright edge of said fold, the other of these positions at an angle thereto.
2. A collar as claimed in claim 1 in which the two pockets have their lower part in common.
3. A collar as claimed in claim 1 in which said second pair of rows of stitching is at the upper end bridged by a transverse row of stitching to form a closed triangle of stitches.

LOUIS L. GOLDENKOFF.
